UNITED STATES PATENT OFFICE.

JAMES JOHN O'HARE, OF MELROSE, MASSACHUSETTS.

DEVICE FOR SCAFFOLDS AND THE LIKE.

Application filed October 10, 1919. Serial No. 329,736.

To all whom it may concern:

Be it known that I, JAMES J. O'HARE, a citizen of the United States, and resident of Melrose, in the county of Middlesex and 5 State of Massachusetts, have invented a new and useful Device for Scaffolds and the like, of which the following is a specification.

The main object of my invention is to provide a device which will hold two poles, 10 one above the other, in proper relation for the purposes of scaffolding and a special object is to construct such a device so that ledgers, or ledger boards, may be applied at two sides of the device, whether the latter 15 is used as a corner post or as an intermediate post.

A feature of my invention consists in providing retaining means to prevent transverse movement of the posts and means to 20 support the device on a lower post but so constructing the device that two sides are substantially open, these two sides being opposite to each other in the case of an intermediate post and being adjacent to each 25 other in the case of a corner post.

Another feature consists in making all the parts permanently fixed in operative 30 position and preferably integral which is very important from the standpoint of strength and cheapness.

Another feature is a peculiar projecting ledge to aid in the support of a ledger board.

Other features will be pointed out be- 35 low.

In the drawing—

Figure 1 is a perspective view of portions of two poles;

Figure 2 is a perspective view of one 40 form of my device;

Figure 3 is a perspective view of another form;

Figure 4 is a section on line 4—4 of Figure 2;

Figure 5 is a section on line 5—5 of Figure 3; and

Figure 6 is a fragmentary elevation of the form of Figure 3.

A and B represent, partly broken away, 50 two poles, my device being adapted to rest on pole A and adapted to hold pole B in position over pole A.

In Figure 2 I show one form of my de- 55 vice preferably used to form with the poles

an intermediate post of the scaffolding, this 55 form preferably consisting of a single casting comprising two vertical opposite walls C and D, a transverse inner partition of wall M and retaining strips E, F, G, H, J and K. The portion M rests on top of pole 60 A and supports pole B. The retaining strips E and F prevent transverse movement of pole B, the strips J and K prevent transverse movement of pole A with relation to the device and strips G and H prevent undesired movement of both poles with relation to the device. It will be observed that two opposite sides are entirely open except for the strips which are spaced apart and this construction permits the attachment, by 70 nails or otherwise, of the desired number of ledger boards, not only at one side but at two sides of the device and also gives a wide range of location for any ledger board because the height of the latter is much 75 less ordinarily than the vertical distance between retaining strips and therefore the ledger board may be attached to any convenient height, this choice of location being an important feature of my invention. 80

In Figure 3 the vertical walls C' and D' are contiguous and at right angles to each other, the retaining strips E' and F' connecting the walls at the top, the strips G' and H' connecting them at the centre and 85 the strips J' and K' connecting them at the bottom. This form includes the partition M' and it is also preferably made from a single casting. This form in conjunction with the poles is preferably used as a corner post for scaffolding, the ledger boards being attached at the two open sides and being at right angles to each other. 90

In this form I also provide the extensive choice of location of the ledger boards de- 95 scribed above in connection with Figure 2. I preferably provide horizontal projections N and N' for support of the ledger board P in case said board is to be used at the height of either of said projections and additional holding of the board P is provided by nails such as P' engaging the pole A, it being understood that the board P is ordinarily held in position by nailing but that the projections N and N' may be used for additional support. 100

The device will be preferably made of such dimensions that the vertical edges of

the walls will be pretty nearly flush with the adjacent surface of the pole so that the ledger board may be conveniently nailed to the pole.

5 Among the advantages of my device I may point out that it is very cheap and serviceable, that its parts are always assembled and ready for immediate use, that it permits a large choice of location of 10 the ledger board and that it provides two open sides for the attachment of the ledger boards.

What I claim is:

1. A device of the character described 15 comprising two vertical walls, one having an internal projection to support the device on a pole and to support another pole; and strips fixed to said walls to act with said walls as retaining means for the poles, said 20 strips being spaced apart to permit the attachment of ledger boards to the poles at two sides of the latter.

2. A device of the character described comprising two vertical walls, one having 25 an internal integral projection to support the device on a pole and to support another pole; and strips integral with said walls to act with said walls to prevent undesired

relative transverse movement of the poles and the device itself, said strips being spaced 30 apart to permit the attachment of ledger boards to the poles at two sides of the latter.

3. A device of the character described comprising two vertical walls at substantially right angles to each other, one having 35 an integral internal projection to support the device on a pole and to support another pole; and substantially right-angled strips connecting and integral with, said walls to act with said walls to prevent undesired 40 relative transverse movement of the poles and the device itself, the device being substantially open at two sides, and said strips being spaced apart to permit the attachment to the poles of ledger boards at substantially 45 right angles to each other.

4. A device of the character described comprising two walls; retaining strips supported by the walls; transversely extending means within the device to support the 50 device on a pole, the device being substantially open at two sides; and a horizontal portion extending outwardly from one of said strips to support a ledger board but permitting nailing of the latter to a pole.

JAMES JOHN O'HARE.
